(57) **CLAIM**

The ornamental design for a urinary device, as shown and described.

DESCRIPTION

FIG. 1 shows a rear perspective view of an embodiment of the urinary device;

FIG. 2 shows a front elevation view of the urinary device shown in FIG. 1;

FIG. 3 shows a left elevation view of the urinary device shown in FIG. 1;

FIG. 4 shows a right elevation view of the urinary device shown in FIG. 1;

FIG. 5 shows a rear elevation view of the urinary device shown in FIG. 1;

FIG. 6 shows a top plan view of the urinary device shown in FIG. 1; and,

FIG. 7 shows a bottom plan view of the urinary device shown in FIG. 1.

Details shown in broken lines illustrate portions of the urinary device that form no part of the claimed design.

1 Claim, 4 Drawing Sheets
